UNITED STATES PATENT OFFICE

150,652

DESIGN FOR A CONTROL BUTTON FOR ELECTRIC IRON

John N. Polivka, Minneapolis, Minn., and Francesco Collura, New York, N. Y., assignors to General Mills, Inc., a corporation of Delaware

Application February 1, 1946, Serial No. 126,158

Term of patent 14 years

(Cl. D49—6)

To all whom it may concern:

Be it known that John N. Polivka and Francesco Collura, citizens of the United States and residents thereof, and of Minneapolis and New York, in the counties of Hennepin and New York, and States of Minnesota and New York, respectively, have invented certain new, original, and ornamental Design for a Control Button for Electric Iron, of which the following is a specification, reference being had to the accompanying drawing, forming a part thereof.

Figure 1 is a top plan view of the control button for electric iron, showing our new design; and

Fig. 2 is a side elevation of the same.

The dominant features of the design disclosed

reside in the surface ornamentation as best shown in Fig. 1.

We claim:

The ornamental design for a control button for electric iron, as shown and described.

JOHN N. POLIVKA.
FRANCESCO COLLURA.
